Int. Cl. D24—02; D9—04

U.S. Cl. D83—1

FIGURE 1 is a medical diagnostic test kit or similar article showing my new design;

FIGURE 2 is a view in perspective of the transparent sleeve of the medical diagnostic test kit of FIGURE 1;

FIGURE 3 is an exploded perspective view thereof; with portions fragmentarily shown in section;

FIGURE 4 is an end elevation looking in the direction of line 4—4 of FIGURE 3.

FIGURE 5 is a vertical cross-sectional thereof; taken on lines 5—5 of FIGURE 3;

FIGURE 6 is a vertical cross-section thereof; taken along the lines 6—6 of FIGURE 1;

FIGURE 7 is a vertical cross-section thereof; taken along lines 7—7 of FIGURE 1;

FIGURE 8 is a plan view thereof; with the transparent sleeve omitted;

FIGURE 9 is a side elevation thereof; with the transparent sleeve omitted;

FIGURE 10 is a horizontal cross-section thereof; with the transparent sleeve omitted taken along the lines 10—10 of FIGURE 8.

This application is a continuation-in-part of my application D. 7,303 filed May 29, 1967 now abandoned.

I claim:

The ornamental design for a medical diagnostic test kit or similar article, as shown and described.
